THERMOSTATIC SWITCH

Filed May 5, 1944

UNITED STATES PATENT OFFICE

2,435,004

THERMOSTATIC SWITCH

Sidney Healey, Washington, D. C., assignor, by
mesne assignments, to American Instrument
Co., Inc., a corporation of Maryland

Application May 5, 1944, Serial No. 534,329

4 Claims. (Cl. 200—138)

1

My invention relates broadly to thermostatic regulators and more particularly to an improved construction for increasing the efficiency and accuracy of thermostatic regulators.

One of the objects of my invention is to provide a construction of thermostatic regulator having means for minimizing losses by heat exchange between adjacent surfaces through which the thermostatic regulator may be installed.

Still another object of my invention is to provide a construction of thermostatic regulator in which losses due to detrimental action resulting from electrolytic deterioration of the thermosensitive element in a thermoregulator may be minimized.

Still another object of my invention is to provide a construction of thermoregulator having improved means for supporting the thermosensitive element for improving the efficiency of the regulator.

Other and further objects of my invention reside in an improved construction of thermoregulator as set forth more fully in the specification hereinafter following by reference to the accompanying drawings in which:

Figure 1 is a side elevational view of the thermoregulator of my invention with parts broken away to show the securing means interconnecting the heat insulation supporting tube and the thermosensitive element; Fig. 2 is a top plan view of the thermo-regulator; Fig. 3 is an enlarged fragmentary longitudinal sectional view through the securing means interconnecting the thermosensitive element and the supporting means; Fig. 4 is a transverse sectional view taken on line 4—4 of Fig. 3; Fig. 5 is a side view of the slideable sleeve-like securing means of my invention; and Fig. 6 is a vertical sectional view through the sleeve-like securing means of my invention.

It has been the usual practice in thermoregulators to employ a metallic tube which extends from the main frame of the regulator and provides a supporting means for a helical bimetallic element constituting the thermoregulator. It has been customary to connect such helical bimetallic element to the supporting tube by machined screws. I have found that this point of connection and support is subject to deterioration as a result of electrolytic action brought about by the chemical action of gases and fluids adjacent which the thermoregulator must function and the differences in the electrochemical series of the metals constituting the bimetallic element, the material of the securing screws and the material of the supporting tube. Moreover, the me-

2

talic supporting tube provides a good conductor for heat and cold so that undesirable heat exchange is effected between the interior and exterior surfaces of any cabinet structure or apparatus with which such thermoregulator is associated.

My invention is directed to means which eliminates all of these disadvantages. I employ a supporting tube for a bimetallic element which is formed from heat insulation material which is a substantially non-conductor of heat or cold, thus eliminating heat exchange losses in various installations of the regulator. I form the helical bimetallic element at one end with instruck projections which are arranged to enter aligned recesses in the supporting tube. I provide a resilient sleeve-like member internally grooved to fit over the end of the helical bimetallic element and over the supporting tube of insulation material for securing by wedge action the bimetallic element with respect to the supporting tube. The resilient sleeve-like member is formed from material of substantially the same electrochemical series as the material of the bimetallic element whereby detrimental electrolytic action is avoided. Thus a construction of thermoregulator is provided which may be produced on a quantity production basis inexpensively and which will have very substantially useful life.

30 Referring to the drawings in detail reference character 1 represents the frame structure for the thermoregulator from which extends the central tubular support 2. The casing for the thermoregulator is represented at 3 carried by frame 1. The adjustable contacts for the regulator are represented generally at 4 and 5 which are adjustable from the exterior of the casing of the thermoregulator by control of adjusting knobs 6 and 7. Binding posts 8 and 9 carried by casing 3 connect through spring members represented at 10 and 11 with the adjusting screws which are provided for adjusting contacts 4 and 5. Binding post 12 carried by casing 3 serves as a terminal member for the helical spring 14 which connects 45 to the contact supporting strip shown at 15. Contact supporting strip 15 is supported by insulated member 16 which is carried on the end of rod member 17 which projects through the tubular support 2 to the end of the bimetallic thermosensitive member represented at 18. The end of the helical bimetallic thermosensitive member 18 is riveted as represented at 19 to the end of the rod member 17 and at the opposite end is secured in accordance with my invention to the heat insulated tubular support 20. The heat insulated

tubular support 20 is formed from heat insulation material substantially non-conductive to heat or cold. The tubular support 20 is mounted in the internally recessed socket portion 21 of the tubular support 2. Set screws 22 pass through tubular support 2 and bear against the end of the heat insulated tubular support 20 securing the heat insulated tubular support 20 in position. The opposite end of the heat insulated tubular support is cut on a bias represented at 23 substantially conforming with the helical disposition of the convolutions of the bimetallic member 18. The end of the bimetallic member 18 is forced over the end of the tubular support 20. The tubular support 20 has a pair of recesses 24 formed therein at distances spaced apart substantially less than the width of the helical bimetallic member 18. The end of the bimetallic member 18 contains a pair of instruck projections 25 which are spaced to conform with the spacing of the recesses 24 and serve to key or interlock the helical bimetallic member 18 with the end of the tubular support 20.

In order to maintain the helical bimetallic member 18 in position with respect to the end of tubular support 20 I arrange resilient sleeve member 26 of such size and shape that will fit over the end of tubular support 20 and clamp the end of the helical bimetallic member 18 with respect to the cylindrical wall of tubular support 20. The sleeve-like member 26 is internally recessed as represented at 27 to allow for the thickness of the helical bimetallic member 18 beyond the external diameter of tubular support 20. As sleeve-like member 26 is forced downwardly over the end of tubular support 20 the lugs 25 and bimetallic member 18 are forced into the recesses 24 in tubular support 20 forming interlocking engagement between bimetallic member 18 and the tubular support 20. Sleeve-like member 26 is longitudinally slotted as represented at 28 to insure resiliency and yieldability so that the sleeve-like member 26 serves as a clamping device. The extremity of sleeve-like member 26 is formed on a bias represented at 29 conforming with the helical contour of the convolutions of the bimetallic member 18.

The contact supporting strip 16 carries contact elements 30 and 31 which establish connection with either of the adjustable contacts 4 and 5. A set screw 32 is provided for selectively setting the thermoregulator in any position to which it may be adjusted. Indicator 33 coacting with an appropriate scale 34 is used to determine the adjustment of the device.

A protecting tube 35 may be secured over the helical thermosensitive element 18 and maintained in position with respect thereto by connection with the depending tubular support 2. With this in view the external diameter of sleeve-like member 26 is maintained at a minimum to fit in spacial relation to the internal diameter of the protecting tube 35.

While I have described my invention in one of its preferred embodiments I realize that modifications may be made and I desire it to be understood that no limitations upon my invention are intended other than are imposed by the scope of the appended claims.

What I claim as new and desire to secure by Letters Patent of the United States is as follows:

1. A thermoregulator comprising in combination with a frame structure a contact system mounted within said frame structure, a rod-like actuator extending through said frame structure for controlling said contact system, a tubular

member of thermal insulation material carried by said frame structure and surrounding said rod-like actuator, a thermosensitive element having helically arranged convolutions, said convolutions being connected at one end to said rod-like actuator and a pair of instruck projections carried by the other end of said thermosensitive element and extending into a pair of coating aligned recesses in said tubular member and a sleeve-like member longitudinally slidable over said thermosensitive element and said tubular member for pressing said instruck projections into interlocking engagement with the coating recesses in said tubular member.

15 2. A thermoregulator comprising in combination with a frame structure a contact system mounted within said frame structure, a rod-like actuator extending through said frame structure for controlling said contact system, a tubular member of thermal insulation material carried by said frame structure and surrounding said rod-like actuator, a thermosensitive element having helically arranged convolutions, said thermosensitive element being connected at one end with said rod-like actuator, an instruck projection carried by the opposite end of said thermosensitive element and extending into said tubular member, and a sleeve-like member formed from resilient material of the same electrochemical series as said thermosensitive element and longitudinally movable over said thermosensitive element and said tubular member for engaging said tubular member at one end and said thermosensitive element at the other end for interlocking the instruck projection on said thermosensitive element with said tubular member.

3. A thermoregulator comprising in combination with a frame structure a contact system mounted within said frame structure, a rod-like actuator extending through said frame structure for controlling said contact system, a tubular member of thermal insulation material carried by said frame structure and surrounding said rod-like actuator, a thermosensitive element having helically arranged convolutions, the end convolution of one end of said element being connected with said rod-like actuator, an instruck projection on the end convolution of the opposite end of said thermosensitive element extending into interlocking engagement with an aligned recess in said tubular member and a sleeve-like member slidable over and engageable with said tubular member, said sleeve-like member having an annularly recessed cylindrical offset portion engageable over the end convolution of the last mentioned end of said thermosensitive element for clamping said thermosensitive element with respect to said tubular member and interlocking the instruck projection thereon with the aligned recess in said tubular member.

4. A thermoregulator comprising in combination with a frame structure a contact system mounted within said frame structure, a rod-like actuator extending through said frame structure for controlling said contact system, a tubular member of thermal insulation material carried by said frame structure and surrounding said rod-like actuator, a thermosensitive element having helically arranged convolutions, said convolutions being connected at one end to said rod-like actuator, an instruck rounded projection on said thermosensitive element at the opposite end thereof adapted to engage in an aligned socket recess in said tubular member and a yieldable sleeve-like member having one edge formed on a

bias substantially corresponding with the pitch of the helically arranged convolutions of said thermosensitive element and slideable over said tubular member and the end convolution of said thermosensitive element for interlocking the interstruck projection adjacent the end convolution of said thermosensitive element with said tubular member.
